UNITED STATES PATENT OFFICE.

ADAM OSTHEIMER, OF CLEVELAND, OHIO.

AUTOMATIC THERMOSTATIC CONTROL FOR INCUBATORS.

1,269,112.

Specification of Letters Patent. Patented June 11, 1918.

Application filed October 9, 1916. Serial No. 124,642.

To all whom it may concern:

Be it known that I, ADAM OSTHEIMER, a citizen of the United States, residing at Cleveland, in the county of Cuyahoga and 5 State of Ohio, have invented certain new and useful Improvements in Automatic Thermostatic Controls for Incubators, of which the following is a specification.

The present invention relates to automatic temperature controllers for incubators and the like, an object of the same being to provide novel and efficient means for automatically maintaining constant the temperature in an incubator.

15 Another object of my invention is to provide means for operating an alarm in the event that the temperature should change from a normal predetermined point.

A further object of my invention is to 20 provide a novel operator for opening and closing a ventilator to maintain constant the temperature in an incubator or the like.

A still further object of my invention is 25 to provide a novel electrical means for controlling the ventilator operator, an alarm being automatically operated when the ventilator fails to operate.

A still further object of my invention is 30 to provide a device of the class described which may be installed upon any of the existing types of incubators without material structural alteration of the same.

A still further object of my invention is 35 to provide a device of the class described embodying a novel arrangement of electrical circuits tending to simplify devices of this character and render more economic the maintenance of the same.

Other objects and advantages to be derived from the use of my improved automatic control for incubators will appear 40 from the following detailed description and the claims, taken with an inspection of the accompanying drawings, in which:—

45 Figure 1 is a side elevational view of a controlling mechanism embodying the improvements of my invention, the same being shown applied in operative position, and an incubator top is shown in section;

50 Fig. 2 is a top plan view of the same; Fig. 3 is an enlarged disassembled perspective view of the ventilator operating device;

Fig. 4 is a diagrammatic view of the elec-

trical circuit controlling the ventilator operator; and

Fig. 5 is an enlarged detailed view of the modified form of thermal circuit controller.

Referring more particularly to the drawings, wherein similar characters of reference 55 designate like and corresponding parts throughout the various views, 10 designates the top portion of a standard incubator forming a base for the operating mechanism for my invention.

The top 10 is provided with a ventilating opening 11 in which is mounted a ring 12 forming a seat for the closure 13, said closure being carried by a rocker arm 14, said arm extending radially from a bearing 70 ring 15, said ring being mounted in a frame 16 on bearing screws 17. The frame 16 is connected to the under surface of the top 10 in any suitable manner. A rod 18 extends from the side of the ring opposite to the rod 75 14, the free end of the rod 18 having a counter-weight 19 mounted thereon, said rod being threaded as at 20 to receive said weight, the latter being adjustable thereby.

A shaft 21 is journaled on screws 22 arranged in the frame 16, a rod 23 extending at right-angles from said shaft, the free end of said rod having a wheel 24 thereon to engage the actuating rod 18. A vertical rod 25 extends from the shaft 21 relatively at 80 85 right-angles thereto and to said rod 23, said rod 25 extending through a suitable opening 26 formed in the top 10.

I provide a shock absorbing and return member for normally maintaining the 90 closure 13 in the closed position, said member consisting of a plate 27 provided with a slot 28 to receive the rod 18, said plate being formed with a rod portion 29 threaded on its upper free end to receive a wing nut 95 30. The rod portion 29 extends through a suitable opening in the top 10, a coil spring 31 being interposed between the top and said wing nut, a washer 32 serving to receive the tension of the spring.

I provide means for moving the closure 13 to open position and for again returning the same to closed position, said means including a pair of electro-magnets 33 and 34 mounted on suitable supports 35 and 36 carried by the top 10. The electro-magnets are in the form of solenoids having movable cores 37 and 38, the adjacent ends of said

cores being connected by a link 39. The link 39 is provided with an opening intermediate its ends to accommodate the rod 25.

In order to alternately energize the electro-magnets I provide a switch S of the rotary type, the same having a lever 40 extending therefrom, said lever being formed with a hook 41 on its free end to engage the upper free end of the rod 25. The lever 10 is bent to form a shaft 42 mounted in journals 43. The circuit closing element of the switch S includes an insulating body portion 44 and a contact plate 45, said plate being adapted, at times, to bridge the distance between the brushes 46, 47 and 48 to produce a result which will hereinafter appear.

The brushes 47 and 48 are provided with binding posts 49 and 50 for a purpose which will hereinafter appear. The electrical circuits embodied in the preferred form of my invention are best shown in Fig. 4 in which the main trunk conductor is designated 53, the same leading from a source of electrical energy such as a battery 54 or the like. A 25 thermostat 55 is interposed in the conductor 53, said thermostat forming one terminal of a switch s'. Working circuit conductors are provided designated 56 and 57, the conductor 56 terminating above the switch s' and the conductor 57 terminating below the same. Two binding posts 58 and 59 are mounted on the top 10, the conductor 56 being connected to the binding post 58 and the conductor 57 to the binding post 59.

35 A conductor 61 leads from the binding post 58, the electro-magnet 33 being interposed in said conductor, the free end of the conductor connecting with the binding post 50.

40 A conductor 63 extends from the binding post 59, the electro-magnet 34 being interposed in said conductor, the continuation of said conductor 63 being connected to the brush 46. A return conductor 64 leads from 45 the brush 47 to the battery 54.

The alarm circuits are designated α and α' , the terminals of the circuit α being connected with the brush 46 and at 66 with the conductor 64, the terminals of the circuit α' 50 being connected with the brush 48 and at the point 66 hereinbefore referred to. A buzzer b and a bell b' form the signaling devices in said circuits α and α' , respectively.

The detailed structure of the circuit closer 55 s' is shown to advantage in Fig. 1, a pair of expansion disks 67 being provided, the same being mounted in a frame 68 suspended from the under face of the top 10. A rod 69 extends upwardly through the top 10 60 from said disk members, said rod having a plate 70 on its upper free end. A bracket 71 is mounted adjacent the plate, said bracket having an adjustable contact screw 72 arranged therein, said screw having a 65 contact point 73 for engagement, at times

with the plate 70. An adjustable contact 74 is mounted on the base to be engaged by the plate 70, at times. The bracket 71 is suitably insulated from the base of the device as indicated at 75.

In Fig. 5 a modified form of thermostatic circuit closer is shown, the same being in the form of a usual thermometer 76 having one conductor 77 connected to the bulb thereof and in continual contact with the 75 temperature indicator, which is usually mercury. The circuits to be controlled are connected at the points 78 so that when the mercury rises or varies with the temperature one or the other of the circuits is energized. 80

In operation, assuming that the temperature is normal and that the closure member is in the open position the thermostatic switch s would be in the position shown in Fig. 4. Should the temperature lower owing 85 to the fact that the closure is opened the plate 70 would engage the contact point 74 energizing the conductor 57, the current flowing therethrough to the electro-magnet 34. When in open position the switch S is 90 in the position shown in Fig. 2, that is, all of the brushes 46, 47 and 48 are interconnected. When the electro-magnet 34 is energized the link 39 is moved toward the right, this movement raising the rod 23 and moving 95 the switch from the position shown to that shown in Fig. 4, disconnecting the brush 46 from the other brushes. Raising the arm 23 permits the spring 31 to move the closure 100 13 to the closed position.

This movement of the switch s causes the current to flow through the electro-magnet 34 and buzzer b, thereby operating an alarm. When the closure 13 is moved to the closed position the temperature necessarily rises in 105 the incubator. This will cause the thermostatic switch s' to raise closing the circuit in which the electro-magnet 33 is interposed. Current now flows through the electro-magnet 33, plate 45 of the switch S, through the 110 brush 47, thence through the conductor 64 back to the battery. The electro-magnet acts upon the link to move the arm 25 to the position shown in Fig. 1 which through the medium of the arm 23 acts upon the rod 115 18 to open the closure. As the plate 45 disconnects from the brush 48 current is shunted through the bell b', an alarm being given. When the temperature becomes normal within the incubator the thermostatic switch s' 120 maintains a neutral position and no alarm is given. It will be readily apparent that the device of my invention may be easily applied for use in connection with any of the existing types of incubators. I do not 125 desire to be limited to the exact arrangement of the circuit closing elements or the arrangement of the circuits, since various modifications of the same may be made without departing from the spirit of the inven- 130

tion. The use of the circuit closer disclosed in Fig. 5 is practically identical with that of the thermostatic switch S.

From the above description taken in connection with the accompanying drawings, it is thought that a clear and comprehensive understanding of the construction, operation and advantages of my invention may be had, and while I have shown and described the device as embodying specific structure, I desire that it be understood that such changes may be made in said structure as do not depart from the spirit and scope of the invention as claimed.

Having thus fully described my invention, what I claim as new and desire to secure by Letters Patent, is:—

1. In a device as specified, the combination with a base having a ventilating opening therein, of a frame suspended from said base, a rocker arm journaled in said frame and having a closure on the free end thereof to engage with said ventilating opening, an actuating arm pivoted in said frame to engage said rocker arm, one end of said actuating arm extending through the base, a pair of electro-magnets adapted for alternate operation, said magnets operatively engaged with the free end of said actuating arm, a circuit controller operable by said electro-magnets to alternately energize a signal, and a thermostatic circuit closer within an area to be heated and interposed in the circuit of said electro-magnet to alternately energize the same upon changes in temperature.

2. In a device as specified, the combination with a base having a ventilating opening therein, of a frame mounted beneath said base and having a rocker arm therein, one end of said arm having a closure for said opening, a shock absorber and return member carried by said base to engage said rocker arm, an actuating arm pivoted to said frame and extending through said base, a pair of solenoids on said base, cores operable in said solenoids and operatively connected with said actuating arm, a thermostatic circuit closer interposed in the circuits of said electro-magnets to alternately energize the same upon changes in temperature, and a mechanical circuit closer actuated by said electro-magnets to independently control their respective circuits.

3. In a device as specified, the combination with a base having a ventilating opening therein, of a frame mounted beneath said base, a rocker arm carried thereby, one end of said arm having a closure for the opening, a shaft journaled in said frame, an actuating arm on said shaft extending through the base, a supplemental angularly disposed arm on said shaft positioned parallel with and engaging the rocker arm, a pair of oppositely disposed solenoids on said base, connected cores carried thereby, and said connection engaging the actuating arm to move the rocker arm.

In testimony whereof, I affix my signature hereto.

ADAM OSTHEIMER.
